UNITED STATES PATENT OFFICE.

LEWIS A. BAKER, OF ELGIN, ILLINOIS.

MACHINE FOR FILLING RECEPTACLES WITH LIQUID.

1,036,778.

Specification of Letters Patent. Patented Aug. 27, 1912.

Application filed April 8, 1911. Serial No. 619,777.

To all whom it may concern:

Be it known that I, LEWIS A. BAKER, a citizen of the United States, and a resident of Elgin, in the county of Kane and State 5 of Illinois, have invented certain new and useful Improvements in Machines for Filling Receptacles with Liquid; and I do hereby declare that the following is a full, clear, and exact description thereof, reference be- 10 ing had to the accompanying drawings, and to the characters of reference marked thereon, which form a part of this specification.

This invention relates to improvements in filling machines of that class in which cans 15 or like receptacles are filled from a common or central liquid tank, the arrangement being such that a plurality of cans are simultaneously filled, and are successively delivered to and discharged from the machine, the filling of the cans or receptacles and their discharge from the machine being automatically effected after the cans or like receptacles are delivered to the machine. The machine is of the general type shown 20 in my prior United States Letters Patent, Number 910,265, dated January 19th, 1909.

Among the objects of the invention is to provide an improved adjustable measuring device by which the contents fed to the receptacles may be accurately measured and maintained by a displacing element arranged to be adjusted to the charge measuring chamber.

A further object of the invention is to 35 provide an improved automatically operated valve mechanism for controlling the delivery of the measured charges to the receptacles placed to receive said charges.

A further object of the invention is to 40 provide a simple and improved feeding means for feeding the cans or receptacles to the rotating carrier or platform which supports the receptacles while they are being filled and for discharging the filled cans 45 therefrom.

Other objects of the invention are to improve and simplify filling machines of this general class and the invention consists in the matters hereinafter set forth and more 50 particularly pointed out in the appended claims.

In the drawings,—Figure 1 is a vertical sectional view of a filling machine made in accordance with my invention. Fig. 2 is a plan view thereof. Fig. 3 is a horizontal 55 section on the indirect line 3—3 of Fig. 1. Figs. 4 and 5 are detail sections showing the measuring chambers, valve mechanism therefor and the displacing elements for varying the charge delivered from said chambers, 60 together with the means for supporting the cans and presenting the cans to the measuring chambers. Figs. 6 and 7 are horizontal detail sections illustrating the valve parts for the measuring chambers and the means 65 for controlling said parts.

The base 10 of the machine has a central raised portion 11 in which is fixed the lower end of a post or standard 12. A sleeve 14 surrounds and rotates on said standard and 70 to the lower end of the sleeve 14 is fixed a large beveled gear wheel 15 which meshes with a pinion 16 of a driving shaft 17 that it mounted in a bearing 18 of said base and a standard 19 and is provided with light 75 and loose pulleys 20, 21. Said sleeve carries at its upper end to rotate therewith a reservoir consisting of a bottom plate 24 and a sheet metal surrounding wall 24'. The hub 25 of the bottom plate is loosely mounted on the sleeve 14. The reservoir may be raised and lowered to adapt the machine to cans of different heights by means of a sleeve 26 screw-threaded to the sleeve 14 and supporting the reservoir through roller 80 bearings interposed between said hub and sleeve. The said sleeve 26 is formed with a beveled gear wheel 27 that meshes with a pinion 28 carried by an adjusting shaft 29 that is mounted in a bearing 30 depending 85 from the bottom of the reservoir and having a hand wheel 31, whereby the sleeve 26 may be raised and lowered to raise and lower the reservoir.

32 designates an annular, horizontal plat- 95 form or carrier arranged beneath the reservoir and keyed or otherwise non-rotatively fixed to the sleeve 14 to rotate therewith and with the reservoir. The platform 32 is provided near its periphery and above the same 100 with angularly separated gage plates 33 upon which the cans A to be filled are di-

rectly delivered and from which the filled cans are discharged. They have flaring marginal rims which guide and hold the cans in place. The said gage plates are vertically movable relatively to the platform 32 and are directly supported by the upright lift rods 34 which are guided in bearings 35, that depend from and are attached to the carrier. Said lift rods are provided 10 at their lower ends with bearing wheels or rollers 37 which rest and roll on a cam ring 38 that is supported on brackets 39 fixed to the upright portion 11 of the base 10. The platform is provided at its marginal portion 15 with radial openings 40 over which the gage plates are supported, and the gage plates are provided at their inner ends or hubs with lugs 41 which engage the inner ends of the openings 40 to hold the gage plates in their proper radial positions during the rising and falling movements thereof.

Arranged above and in alignment with the gage plates are a plurality of charge 25 measuring chambers 45 consisting of hollow cylinders which are open at their upper ends and which extend through openings in and are supported on the bottom of the supply reservoir. Said measuring chambers 30 are closed at their lower ends by end walls 46 which terminate in filling nipples 47 that are adapted to register with the openings *b* in the cans or receptacles *B*. Automatically operated valves 48 coöperate 35 with said nipples 47 to control the discharge of the material from said chambers to the cans below, as will hereinafter more fully appear. The chambers are shown as provided between their ends with exterior, 40 conical or beveled annular flanges 49 which fit conical, upwardly facing seats in said bottom wall surrounding the openings through which the chambers extend, and are clamped in place by the lock nuts 50, which 45 are screw-threaded to the chambers below, and bear upwardly against the lower side of said reservoir bottom wall. In this manner a fluid tight joint is provided, the integrity of which may be insured by the 50 interposition of a suitable packing between the tapered parts if desired.

Supported within the upper open ends of the charge measuring chambers are displacing elements 52 which fit closely within 55 said chambers and extend a distance above the same, and are adapted to be adjusted vertically therein. Said displacing elements, as herein shown, take the form of cylinders to conform to the illustrated cross section 60 of the charge measuring chambers, and will in any event closely fit and correspond in cross section to said chambers. The said displacing elements are supported in the charge measuring chambers by means permitting vertical adjustment of the displac-

ing elements in said chambers whereby to vary the capacity of the charge measuring chambers to suit a given size can to be filled, and are further formed with parts that coöperate to constitute valves by which the flow of material from the reservoir to the charge measuring chambers is controlled. As herein shown these results are effected by the following construction:— Surrounding the upper ends of the charge 75 measuring chambers are split clamping rings 53 which are annularly grooved at their lower sides to fit over or interlock with radial flanges 54 surrounding the open upper ends of said chambers. Said rings 80 have cylindric flanged portions 55 which closely embrace the displacing cylinders 52, and are provided at their ends with lugs 56 (Fig. 1) through which extend clamping bolts 57. By loosening the clamping rings 85 the displacing cylinders may be moved upwardly or downwardly to the proper point to adjust the charge measuring space in the chambers 45, below the cylinders, to receive a predetermined charge of material for filling a certain size of can, and when the clamping rings are tightened the displacing cylinders are locked from vertical movement therein. The displacing cylinders may be provided with graduation marks 58 to be 90 read from the tops of the clamping rings by which to adjust the cylinders. In order that the displacing cylinders may be removed from the charge measuring chambers without releasing the clamping bolts 95 57, the lower lips 59 of the clamping rings are notched, as shown at 60 (Figs. 6 and 7) to pass over the flanged lugs 54 at the upper ends of the chambers (see dotted lines 100 in Figs. 6 and 7). The parts are locked together by turning the clamping rings to bring the notches out of line with the flanged lugs, as indicated in said Figs. 6 and 7.

The means herein shown for controlling 110 the admission of the material from the reservoir to the charge measuring chambers are made as follows:—Said chambers are provided at the bottom wall of the reservoir with inlet ports 65. The displacing cylinders extend below the level of said ports and are provided at their sides with elongated, vertical ports 66 which open entirely to the bottoms of the cylinders. When the cylinder ports are opposite the chamber 115 ports, as shown in Figs. 5 and 7, the material is free to flow from the reservoir into the charge measuring chambers to fill the latter, but when the cylinders are turned to bring their elongated ports 66 angularly 120 out of line with the chamber ports 65 the walls of the displacing cylinders close said chamber ports, as shown in Figs. 4 and 6, and constitute valves to shut off the flow of material to said charge measuring cham- 125 130

bers. Means hereinafter described are provided for turning the cylinders in proper timed relation relatively to the other operations of the machine for alternately opening and closing the valves thus constructed and arranged. The cylinder ports are made considerably longer than the chamber ports 65 in order to adapt the longer ports to all vertical adjustments of said cylinder. Preferably, and as herein shown, the displacing cylinders or elements are made hollow, being made of sheet metal with top and bottom ends walls, and the elongated ports 66 thereof are formed in suitable concave indentations, as best shown in Figs. 5, 6 and 7.

The measured charges of material are discharged from the chambers through the filling nozzles 47 into cans or bottles below when the valves 48 are opened. Said valves 48 are provided with stems 69 that extend upwardly through tubular guides 70 in the hollow displacing cylinders and above the cylinders and are adapted at their upper ends for connection with valve actuating means.

Referring now to the means for operating the inlet and outlet valve mechanism for the charge measuring chambers, it will be observed that the charge measuring chambers 30 are spaced angularly around the reservoir and travel in a circular path in the rotation of the latter, and that the can gages 33 are likewise disposed on the platform or carrier 32 and travel therewith to hold the cans 35 vertically beneath the filling nozzles 47 of said charge measuring chambers. The clamping or locking rings 53 are provided at the inner sides of the chambers 45 with short arms 74, 75, the latter arms being 40 provided at the upper sides of their inner ends with upstanding roller bearing studs 76 and the former arms being provided at the lower sides of their inner ends with downwardly extending studs 77. The 45 upstanding roller bearing studs are adapted to strike, once during each cycle of their revoluble movement, a fixed tripping cam 78 (Figs. 1 and 2) carried by an arm 79, the hub 80 of which is non-rotatively fixed to 50 the upper end of the standard 12. The downwardly extending studs 77 of the arms 74 are adapted, in a like manner, to strike the outer end of a tripping arm 81 carried by a member 82 which is shown as made integral with said hub 80. The said fixed tripping cam and arm are angularly spaced at substantially 120 degrees apart, as herein shown, and the parts are so arranged that when the tripping cam 78 acts upon the 60 roller bearing studs of the arms 75 of the clamping rings 53 and the displacing cylinders are turned to bring the ports 65 and 66 out of register, as shown in Fig. 6, so as to close the charge measuring chamber inlet valves. When the studs 77 strike the trip-

ping arm 81, said displacing cylinders are turned or rotated to bring the ports 65 and 66 into register and thus open the reservoir to the charge measuring chambers. It will thus be seen that, in the arrangement shown, the inlet valves of the charge measuring chambers, comprising the ports 65 and 66, remain open throughout substantially one-third of the rotative travel of the chambers, and will remain closed throughout the remaining two-thirds of the travel. During substantially all the time when the inlet valves are closed the outlet valves are opened to permit the material to flow from the charge measuring chambers to the cans beneath.

The mechanism herein shown for controlling the outlet valves is made as follows:—The cam ring 38 is formed with a low portion α and a high portion α' . The low portion α of the cam ring 38 is made slightly longer than the angular distance between the tripping arm 81 and the tripping cam 78 and is connected to the high portion of the cam ring by the cam portions α^2 , α^3 , the former of which is shown in Figs. 1 and 5 and both of which are indicated in dotted lines in Fig. 3; the cam portion α^2 being the ascending portion, and the cam portion α^3 being the descending portion of the cam ring.

The mechanism for opening and closing the outlet valves to discharge the material from the charge measuring chambers to the cans is so arranged that said outlet valves are closed during the time the rollers 37 of the lifting bars 34 are traveling on the low portion α of the cam ring, during which time the inlet valves to the charge measuring chambers are open, having been opened by the arm 81; and said outlet valves are open just after the inlet valves have been closed through the action of the tripping cam 78. The unfilled cans are delivered to the machine at the time the outlet valves are closed and while the charge measuring chambers are being filled, and the filled cans are discharged from the machine just after the outlet valves have been closed and the inlet valves to the charge measuring chambers have been opened.

The means for opening the outlet valves, under the control of the cam ring 38, are made as follows:—85, 85 designate vertically movable lift bars, one for each charge measuring chamber, arranged outside of the reservoir and guided in suitable guides 86, 87 attached to the wall 24' of said reservoir. To the upper ends of the lift bars are attached brackets 88 which carry inwardly directed arms 89 that engage under suitably shaped heads 91 fixed to the upper ends of the stems 69 of the discharge valves 48. Said arms 89 are pivoted to the brackets 88 at 92 so that the arms may be swung up-

130

wardly and outwardly over the brackets to permit the displacing cylinders 52 to be raised out of the charge measuring chambers for the purpose of cleaning the latter. 5 Fixedly attached to the lower ends of the lift bars 85 are forked members 93, one arranged below each charge measuring chamber, and arranged when in their lowermost position a distance above the gage plates 33 10 slightly greater than the height of the cans or other receptacles to be filled, so that the cans may be freely delivered thereunder by the can delivering mechanism hereinafter described. The forked members 93 are attached to the lift bars by set screws 94 to permit them to be adjusted vertically, within a limited range, to adjust the machine to cans of different heights.

The cans are delivered upon the gage plates when the rollers 37 of the lifting rods 34 are riding on the low portion a of the cam ring 38 and when, therefore, the gage plates are in their lowermost positions. As the platform or carrier 32 revolves with a can on one of the gage plates, when the latter is in its lowermost position, the roller 37 of the lifting rod 34 of said gage plate strikes the rising portion a^2 of the cam ring just after the inlet valve of the charge measuring chamber associated therewith has been closed through the action of the tripping cam 78. As each roller 37 rides up the rising portion a^2 of the cam ring to the high portion a' it lifts the associated can to bring the opening thereof to the nozzle 47 of the charge measuring chamber, and at the same time acts, through the forked member 93 and lifting bar 85 to raise the outlet valve 48 to permit the material to flow from the charge measuring chamber to the can. The said outlet valve is held in its open position, as indicated in Fig. 4, until the roller 37 of the lifting rod 34 strikes the descending portion a^3 of the cam ring 38, whereupon the outlet valve is closed. The outlet valve is thus closed just before the trip arm 81 acts upon the stud 77 to rotate the displacing cylinder 52 and to open the inlet valve. It will thus be seen that charge measuring chambers are 50 emptying into cans below throughout substantially two-thirds of the travel thereof in their circular path of movement, thus giving time to permit the contents of the chambers to be entirely discharged into the cans, and 55 to avoid dripping of the material from the discharge nozzles after the filled cans have been discharged from the machine.

The space beneath that part of the machine between the inlet valve opening arm 80 81 and the inlet valve closing cam 78, which as herein shown includes about one-third of the travel of the charge measuring chambers, is utilized to discharge the filled cans from the machine and to deliver the empty 65 cans to the machine. The mechanism for

delivering the cans to the machine and discharging them therefrom will now be described.

95 designates a horizontal table arranged at one side of the machine in the plane of the carrier 32, and is supported in part by a standard 96. 97 designates a sprocket chain or belt which is trained about sprocket wheels 98, 99 rotatively mounted on suitable bearing studs 100, 101 carried by said table and the inner end of a plate 102, respectively, the latter arranged radial to the standard 12, with its inner end and the sprocket wheel 99 over the carrier 32. Said sprocket chain is provided at suitably spaced intervals with 75 outwardly directed arms 104 which engage the empty cans to carry them inwardly over the table to the gage plates 33 at the receiving side of the machine, and to carry the filled cans away from the gage plates at the discharge side of the machine. The empty cans are shown as delivered into the path of the arms 104 at the receiving side of the machine by a notched disk 106 rotatively mounted over the table on a stud 107, the 80 cans being placed in the notches of the disk, either manually or automatically as desired, and being held therein and guided into the path of the chain arms by the guard bar 108. The speed of the can feed chain is so 85 timed with respect to the speed of the carrier that as each empty can is delivered to the carrier by an arm 104 one of the gage plates 33 is in position to receive the can. The relation of the parts are also such that the can feed chain arms 104 engage the filled cans as they are discharged from the rotative carrier and directs them to a take off belt 109 by which the filled cans are directed from the machine to any suitable 90 place for the disposal therefor. The cans are forced into place onto the gage plates by means of a yielding cam arm or guide 110 pivoted to the table at 111, the inward movement of said cam being limited by a stop 110 pin 112 working in a slot therein, and said cam being pressed inwardly by a spring 113. The said notched disk 106 is driven by a train of gears 114, 115, 116 indicated in dotted lines in Fig. 3. The gear wheel 114 115 is fixed to a shaft 117 on the lower end of which, below the table, is mounted a star wheel 118, the notches of which are adapted to engage the bearings 35 for the lift rods 34, whereby said tooth wheel 118 and the 120 gears connected therewith are rotated. The can feed chain 97 is also driven from the train of gears described through the medium of a gear wheel 120 which meshes with the gear wheel 115 and with a pinion 121 mounted on the lower end of the shaft 100 on which the sprocket 98 is mounted.

The filled cans are removed from the gage plates of the carrier by means of the curved stripper bar 125 which, as herein shown, is 130

fixed to the arm or plate 102 which carries the can delivering chain sprocket wheels. Said stripper bar is arranged above the level of the chain 97 and arms 104 and extends inwardly at its inner end over the gage plates to a point beyond the receptacles supported thereon. When the receptacles are brought against the outer curved edge of the stripper bar, during the rotation of the carrier, they are started off the gage plates toward the table 95, whereby said filled cans are in motion when they are engaged by the arms 104. Thus the cans are gently moved by said arms, and without objectionable shock 15 toward and onto the take off belt 109. The filled cans are guided onto the belt between the stripper bar and a short guide bar 127 arranged at one side thereof, as shown in Figs. 2 and 3. The take off belt is trained 20 about a pulley 128, shown in dotted lines in said Figs. 3 and 4, the shaft 129 of which is driven by a sprocket belt 130 that is trained over a sprocket wheel 131 of said shaft 129 and a sprocket wheel 132 fixed to a short 25 shaft 133, the inner end of which latter carries a beveled pinion 134 that meshes with the beveled gear wheel 15, as shown in dotted lines in Fig. 3.

The machine herein described may be used 30 for filling cans with any fluid-like material, such as fruit extracts, syrups, jellies, milk and the like, and is especially adaptable for filling cans with relatively heavy and slow flowing liquids or syrups, because of the 35 time given for the liquid to be discharged into the cans after the charge measuring receptacle has been filled and the inlet valves thereof closed.

The operation of the machine will be clear 40 from the foregoing, but may be briefly recapitulated as follows:—The empty cans are placed in the notches of the notched disk 106, either by hand or automatically, and are carried thereby into the path of the arms 104 45 of the feed chain, by which they are delivered to the gage plates. At the time the cans are delivered to the gage plates the outlet valves of the charge measuring chambers immediately over said cans are closed, and 50 the inlet valves of said latter measuring chambers are open. In the continued rotation of the carrier 32 the bearing rollers 37 of the lifting rods 34 ride up on the inclined cam surface a^2 of the cam ring 38 and lift 55 the cans up to the discharge nozzles of said chambers and also open the outlet valves 48; and said outlet valves remain open until the bearing rollers of the lifting rods 34 roll down on the descending portion a^3 of the 60 cam ring, at which time the outlet valves are closed. Before the outlet valves are opened the tripping cam 78 strikes the roller bearing studs of the arms 78 of the displacing elements or cylinders and rotate the displacing 65 elements to close the inlet valves of the

charge measuring chambers so that only the amount of liquid delivered to the charge measuring chambers is delivered to the cans. Said inlet valves remain closed until after all of the material from the charge measuring chambers has been discharged into the cans and the discharge valves are closed. The inlet valves are opened by contact of the tripping arm 81 with the studs 77 of the arm 74 of the rotative displacing element and the measuring chambers are filled at the time the filled cans are being discharged from the machine and empty cans are being delivered thereto.

It will be obvious that the structural details of the machine illustrated and described may be varied within the spirit and scope of my invention, and the invention is not limited to such details except as such limitations are imposed by the prior art.

I claim as my invention:—

1. In a filling machine, a charge measuring chamber having a valve controlled outlet, and a displacing element mounted in said chamber to rotate and to be adjusted endwise therein, and means adapted by rotative movement of said element to control the inlet of material to the charge measuring chamber.

2. In a filling machine, a charge measuring chamber having a valve controlled outlet, a displacing element mounted in said chamber to rotate and to be adjusted endwise therein, with means to lock the displacing element in adjusted position, said displacing element and chamber being provided with ports to constitute an inlet valve, and adapted by rotation of the displacing element to control the inlet of material to the charge measuring chamber.

3. In a filling machine, a charge measuring chamber having a valve controlled outlet, a displacing element mounted in said chamber to rotate and to be adjusted endwise therein, with means to lock the displacing element in adjusted positions, said displacing element and chamber being provided with ports to constitute an inlet valve and adapted by rotation of the displacing element to control the inlet of material to the charge measuring chamber, means for opening and closing the outlet valve and means operated in timed relation to the controlling movement of the inlet valve for rotating the displacing element to open and close the inlet valve.

4. In a filling machine, a charge measuring chamber provided with a valve controlled outlet, a displacing element in said chamber, a clamping ring mounted on said chamber and arranged to be clamped on the displacing element, thereby permitting the displacing element to be moved a greater or less distance into the chamber and to be locked into adjusted positions, and means

associated with the displacing element and the chamber to control the inlet of material to the measuring chamber.

5. In a filling machine, a charge measuring chamber provided with a valve controlled outlet, a displacing element in said chamber, a clamping ring mounted on said chamber and arranged to be clamped on the displacing element, thereby permitting the displacing element to be moved a greater or less distance into the chamber and to be locked into adjusted positions, means associated with the displacing element and the chamber to control the inlet of material to the measuring chamber, and means for releasably locking the clamping ring to the wall of said chamber.
10. In a filling machine, a charge measuring chamber having a valve controlled outlet, a displacing element mounted in said chamber to rotate and to be adjusted endwise therein, said displacing element and chamber being provided with ports adapted, by rotation of the displacing element, to control the inlet of material to the charging chamber, a clamping ring rotatively mounted on the chamber and adapted to be clamped on the displacing element to fix the displacing element in endwise adjusted relation to the chamber, said ring being provided with means by which to rotate the clamping ring and displacing element.
20. In a filling machine, a charge measuring chamber having a valve controlled outlet and provided with an inlet port, a displacing element mounted in the chamber to rotate therein and provided with a port to register with the port of the chamber, and means to rotate the displacing element to move its port into and out of register with the port of the chamber.
30. In a filling machine, a charge measuring chamber having a valve controlled outlet and provided with an inlet port, a displacing element mounted in the chamber to rotate therein and provided with an elongated port to register with the port of the chamber, and means to rotate the displacing element to move its port into and out of register with the port of the chamber, said displacing element being adjustable endwise of the chamber and provided with means to fix it in adjusted positions therein to vary the capacity of the chamber.

40. In a filling machine, a charge measuring chamber having an outlet, a displacing element mounted in the chamber to rotate therein and movable endwise to vary the capacity of the chamber, with means for fixing it in adjusted positions, said displacing element and the chamber having ports to constitute the inlet valve of the chamber which is controlled by rotation of the displacing element, and the displacing element being provided with an axial opening, and

a valve for controlling the outlet of the chamber provided with a stem extending through said axial opening and provided at its outer end with means whereby said valve may be actuated.

5. A filling machine comprising a rotary reservoir with means for rotating it, a circular row of charge measuring chambers supported on and adapted to communicate with the reservoir through inlet valves, said chambers being provided with outlet valves, inlet valve controlling means stationary with the machine adapted to open the valves at one point in the circular path of movement of the chambers and to close them at another point in said path, and means for opening and closing the outlet valves, arranged to open the latter valves after the inlet valves have been closed, and to close the same before the inlet valves are open, to thereby measure the charges of material before being discharged from said chambers.

10. A filling machine comprising a rotative reservoir with means for rotating it, a circular series of charge measuring chambers concentric with and supported on and adapted to communicate with the reservoir through inlet valves, said chambers being provided with outlet valves with means to actuate the same, displacing elements in said chambers adjustable to vary the capacity of the chambers and having a limited turning movement therein, the inlet valves to the charge measuring chambers embracing ports in the displacing elements and chambers, controlled by turning movement of the displacing elements in the chambers, and means stationary with the machine for rocking or turning said displacing elements to open and close the inlet valves.

10. A filling machine comprising a standard, a reservoir rotatively supported thereon, a circular series of charge measuring chambers supported on and adapted to receive material from said reservoir, with inlet valves for controlling the admission of material to said chambers, outlet valves for said chambers, with means to control the same, and angularly spaced arms carried by said standard for actuating said inlet valves.

12. A filling machine comprising a rotative reservoir with means for rotating it, a circular row of chambers carried by and adapted to receive material from said reservoir and provided with outlet valves, means for presenting receptacles to said outlet valves, displacing elements in the chambers to vary the capacity thereof, said displacing elements being movable to control the flow of material from the reservoir to the chambers, means carried by a fixed part of the machine and acting on the displacing elements during the rotation of the reservoir to actuate said elements to open

and to close communication between the reservoir and said chambers, and a fixed cam device acting on the outlet valves for opening and closing the valves.

- 5 14. A filling machine comprising a rotative reservoir with means for rotating it, a circular row of chambers carried by and adapted to receive material from the reservoir and provided with outlet valves, means 70
10 for presenting the receptacles to said outlet valves, cylinders within and having a limited turning movement in said chambers, the cylinders and chambers having ports adapted, by turning movement of the 75
15 cylinders, to open and close communication between the reservoir and chambers, means carried by a fixed part of the machine and acting on said cylinders during the rotation of the reservoir to actuate the cylinders to 80
20 open and close communication between the reservoir and chambers and a fixed cam device acting on the outlet valves to open and close the same.

- 25 15. A filling machine comprising a standard, a reservoir rotatively supported thereon, a circular series of chambers carried by said reservoir to receive material therefrom, cylinders contained within and having limited rotative movement in the chambers 85
30 and provided with ports adapted, by rotation of the cylinders, to be moved into and out of register with ports in the chamber walls to control the inlet of material to the chambers, means to control the outlet of 90
35 material from said chambers, and angularly spaced arms carried by said standard for actuating said inlet valves.

- 40 16. A filling machine comprising a rotative reservoir with means for rotating it, a carrier beneath and rotating with said reservoir upon which the empty receptacles are fed and from which the filled receptacles are discharged, a cam track for 100
45 raising the receptacles into their filling positions, a circular row of chambers adapted to receive material from the reservoir and provided with valved outlet ends to discharge into the receptacles, means whereby the outlet valves are opened when the receptacles are raised to their filling positions, cylinders contained in said chambers and having a limited turning movement therein and provided with ports adapted to 105
50 co-operate with ports in the chamber walls to constitute inlet valves to control the admission of material from the reservoir to the chambers, stationary means for turning the cylinders in said chambers at one point in the path of movement of the chambers to open the inlet valves, and other stationary means for turning said cylinders at another point in said path to close said inlet valves.

- 55 17. A filling machine comprising a rotative reservoir with means for rotating it, a

carrier beneath and rotating with said reservoir upon which the empty receptacles are fed and from which the filled receptacles are discharged, a cam track for raising the receptacles into their filling positions, a circular row of chambers adapted to receive material from the reservoir and provided with valved outlet ends to discharge into the receptacles, means whereby the outlet valves are opened when the receptacles are raised to their filling positions, cylinders contained in said chambers and having a limited turning movement therein and provided with ports adapted to co-operate with ports in the chamber walls to constitute inlet valves to 110
75 control the admission of material from the reservoir to the chambers, stationary means for turning the cylinders in said chambers at one point in the path of movement of the chambers to open the inlet valves, and other stationary means for turning said cylinders at another point in said path to close said inlet valves, said cylinders being longitudinally adjustable in the chambers to vary by displacement the capacity of the chambers. 90

18. A filling machine comprising a rotative reservoir with means for rotating it, an annular series of gage plates beneath and rotating with the reservoir upon which the empty receptacles are fed and from which the filled receptacles are discharged, a cam track acting on the gage plates for raising the receptacles into their filling positions, an annular series of charge measuring chambers provided at their lower ends with outlet passages arranged to discharge into said receptacles and having valves for controlling the same, displacing elements mounted in said chambers to rotate, and adjustable endwise, therein and adapted by 120
95 rotative movement thereof to control the flow of material from the reservoir to the charge measuring chambers, means stationary with the machine to act on the displacing elements to open and close communication between the reservoir and said chambers, and means actuated by the receptacles when raised to their filling positions to open the outlet valves. 110

19. A filling machine comprising a rotative reservoir with means for rotating it, an annular series of gage plates beneath and rotating with the reservoir upon which the empty receptacles are fed and from which the filled receptacles are discharged, a cam track acting on the gage plates for raising the receptacles into their filling positions, an annular series of charge measuring chambers provided at their lower ends with outlet passages arranged to discharge into said receptacles, and having valves for controlling the same, displacing elements mounted in said chambers to rotate, and adjustable endwise, therein and adapted by 125
115 rotative movement thereof to control the flow of material from the reservoir to the charge measuring chambers, means stationary with the machine to act on the displacing elements to open and close communication between the reservoir and said chambers, and means actuated by the receptacles when raised to their filling positions to open the outlet valves. 130

flow of material from the reservoir to the charge measuring chambers, means stationary with the machine to act on the displacing elements to open and close communication between the reservoir and said chambers, said outlet valves being provided with stems which extend upwardly through openings in the displacing elements and beyond the latter, and means connected with the upper ends of said stems and actuated by raising of the receptacles to their filling positions to open the outlet valves.

20. A filling machine comprising a rotative reservoir with means for rotating it, a circular series of charge measuring chambers concentric with and supported on and adapted to communicate with the reservoir through inlet valves, said chambers being provided with outlet valves, displacing elements in said chambers adjustable to vary the capacity of the chambers and having a limited turning movement therein, the inlet valves for the charge measuring chambers embracing ports in the displacing elements and chambers, angularly separated inlet valve controlling elements arranged to turn said displacing elements to first open and then close said inlet valves, means acting on the outlet valves to open the outlet valve of each chamber after its inlet valve has been closed and to close the outlet valve before the inlet valve is opened, and means arranged beneath the space between the angularly separated inlet valve controlling elements for delivering the empty receptacles to and discharging them from the machine.

21. A filling machine comprising a reservoir, a rotative annular series of charge measuring chambers with means for rotating the same and having valve inlet mechanism between them and said reservoir, comprising means located at one point of the path of rotary movement of the chambers to open the inlet valves and another point of said path to close the valves, whereby predetermined charges of material are admitted from the reservoir to the chambers, said chambers being provided with outlet valves, with means for opening and closing the same, arranged to open the valve of each chamber when the inlet valve of said chamber is closed and to close the valve before the inlet valve of said chamber is opened, and means arranged beneath the portion of the path of said chambers in which the inlet valves are open and the outlet valves closed to deliver empty receptacles to and discharge filled receptacles from the machine.

22. A filling machine comprising a reservoir, a rotative annular series of charge measuring chambers with means for rotating the same and having valve inlet mechanism between them and said reservoir, comprising means located at one point of the

path of rotary movement of the chambers to open the inlet valves and another point of said path to close the valves, whereby predetermined charges of material are admitted from the reservoir to the chambers, means associated with the inlet valve mechanism for varying the capacity of the chambers, said chambers being provided with outlet valves, with means for opening and closing the same, arranged to open the valve of each chamber when the inlet valve of said chamber is closed and to close the valve before the inlet valve of said chamber is opened, and means arranged beneath the portion of the path of said chambers in which the inlet valves are open and the outlet valves closed to deliver empty receptacles to and discharge filled receptacles from the machine.

23. A filling machine comprising, in combination with a rotatively mounted reservoir, a circular series of charge measuring chambers adapted to receive material from the reservoir, and a carrier below said chambers provided below each chamber with a support for a receptacle, of an endless belt having outwardly directed arms, arranged with the arms at one lap of the belt to carry the empty receptacles to said supports and with the arms at the other lap of the belt to remove the filled receptacles from the machine, inner and outer pulleys about which said belt is trained, the inner pulley being located between the axis of rotation of the carrier and said supports, and driving means applied to one of said pulleys.

24. A filling machine comprising, in combination with a rotatively mounted reservoir, a circular series of charge measuring chambers adapted to receive material from the reservoir, and a carrier below said chambers provided below each chamber with a support for a receptacle, of an endless belt having outwardly directed arms, arranged with the arms at one lap of the belt to carry the empty receptacles to said supports and with the arms at the other lap of the belt to remove the filled receptacles from the machine, inner and outer pulleys about which said belt is trained, the inner pulley being located between the axis of rotation of the carrier and said supports, driving means applied to one of said pulleys, and means for gradually moving the filled receptacles off the supports just before they are engaged by said belt arms.

25. A filling machine embracing a rotative carrier to support the receptacles while being filled, a fixed table at the level of the carrier, an arm extending inwardly from said table over the carrier and provided at its ends with pulleys, a chain trained about said pulleys and provided with outwardly directed arms, with those of one lap of the belt adapted to deliver the empty receptacles

from the table to said carrier and with arms at the other lap of the belt adapted to remove the filled receptacles from the carrier back to the table, guiding means to engage 5 the filled receptacles as they are discharged from the carrier to the table by said arms, and a take-off belt at the level of the table for removing the filled receptacles from the table.

In testimony, that I claim the foregoing 10 as my invention I affix my signature in the presence of two witnesses, this 11th day of March A. D. 1911.

LEWIS A. BAKER.
